We claim the ornamental design for a removable device interface, as shown and described.

DESCRIPTION

This application claims priority from U.S. patent application Ser. No. 13/745,588, entitled "Avionics Data Storage Device and Transfer System with Electro-Opto-Mechanical Identification," filed on Jan. 18, 2013, which is hereby incorporated by reference.

FIG. 1 is a front perspective view of an embodiment of a removable device interface showing our new design;

FIG. 2 is a rear perspective view thereof;

FIG. 3 is a front view thereof;

FIG. 4 is a side view thereof;

FIG. 5 is a top view thereof; and,

FIG. 6 is a bottom view thereof.

Broken lines and entirely unshaded portions contained within broken line are not claimed.
